UNITED STATES PATENT OFFICE.

HARRY C. SMITH AND GEORGE E. LIPPERT, OF CHAGRIN FALLS, OHIO]

ELECTRIC CONTROLLER.

SPECIFICATION forming part of Letters Patent No. 775,317, dated November 22, 1904.

Application filed April 2, 1904. Serial No. 201,296. (No model.)

To all whom it may concern:

Be it known that we, HARRY C. SMITH and GEORGE E. LIPPERT, citizens of the United States, residing at Chagrin Falls, in the county 5 of Cuyahoga and State of Ohio, have invented new and useful Improvements in Electric Controllers, of which the following is a specification.

Our invention pertains to electric controllers and contemplates the provision of a reliable electrical device for stopping and starting an air-compressor or other fluid-pressure apparatus, and thereby regulating the working of the same.

With the foregoing in mind the invention will be fully understood from the following description and claims when taken in connection with the accompanying drawings, forming part of this specification, in which—

Figure 1 is a view, partly in section and partly in elevation, illustrating our novel controller as the same appears when the electric circuit is complete. Fig. 2 is a detail edge elevation of the outer portion of the fixed arm of the controller. Fig. 3 is a similar view of the outer portion of the swinging arm of the controller. Fig. 4 is a detail elevation illustrating the opposite sides of the swinging arm and the contact-piece thereon to those shown in Fig. 1. Fig. 5 is a detail elevation illustrating the position of the swinging arm relative to the fixed arm when the electric circuit is broken. Fig. 6 is a diagrammatic view illustrating our novel controller, together 35 with a source of electric power, a motor, a fluid-pressure pump or compressor, and the electric and fluid pressure connections between the said parts.

Referring by letter to the said drawings, 40 and more particularly to Figs. 1 to 5 thereof, A is the cylinder of the controller constituting the present and preferred embodiment of our invention. The said cylinder is connected at one end to a conduit *a*, designed to lead from 45 an air-compressor or similar device or from a reservoir, is exteriorly threaded at its opposite end, as indicated by *b*, and is provided at an intermediate point of its length with a longitudinal slot *c* and lugs *d*, disposed at 50 opposite sides of said slot.

B is a piston movable in the cylinder A and having a rod *e* and a head *f* and lateral projection *g* on said rod.

C is a cap screwed on the threaded end *b* of the cylinder A and having a central aperture *h* and also having a yoke *i*, provided with an aperture *j*, disposed coincident with the aperture *h*. D is a screw extending loosely through the said apertures *h* and *j* and having a head *k* at its inner end; E, an angular nut disposed between the cap C and its yoke *i* and mounted on and engaging the thread of the screw D, and F a coiled spring contained in the cylinder A and interposed between the head *f* of the piston B and the head *k* of the screw D. The said spring F exerts pressure against the piston B and tends to resist movement of the piston in the direction indicated by arrow in Fig. 1, and its tension may obviously be regulated through the medium of the nut E and the screw D, so as to cause it to resist the movement of the piston in the direction stated to a greater or less extent, as required.

G is a rigid arm, of insulating material, fixedly connected to and extending laterally from the cylinder A and having a recess *l* in one of its sides and at an intermediate point of its length and also having a beveled outer end *m*, Fig. 2. H is a contact-piece fixed in the said recess *l* of arm G, and I is a binding-post carried by the arm G and connected with the fixed contact-piece, as shown by dotted lines in Figs. 1 and 2.

J is a swinging arm which comprises, by preference, an inner portion *n*, of metal, pivotally mounted between the lugs *d* of the cylinder A and extending through the slot *c* of said cylinder and having a slot *p* receiving the lateral projection *g* on the piston-rod *e*, an intermediate portion *q*, of insulating material, and an outer portion *r* of metal. The said outer portion *r* carries a binding-post *s*, a swinging contact-piece *t*, and a coiled spring *u*. The swinging contact-piece *t* is pivotally mounted on a bolt *v*, extending laterally from the portion *r* of arm J, and a coiled spring *w* is interposed between the head of the said bolt and the side of the swinging contact-piece *t*, so as to hold the said contact-piece against the

- arm r under normal conditions and yet enable the said contact-piece to give laterally when it rides over the beveled end of the fixed arm G in the manner presently described.
- 5 The spring u is interposed between and connected to the swinging contact-piece t and the arm portion r and operates to normally hold a nut x or other abutment on the contact-piece t against the edge of the said arm portion r , 10 as shown in Fig. 1.
- In the practical operation of our novel controller the parts rest in the relative positions shown in Fig. 1 so long as the pressure supplied to the cylinder A through pipe a is insufficient to overcome the pressure exerted by the spring F , and hence the electric circuit remains complete and the working of the compressor continues. When, however, the air or other fluid under pressure supplied 15 through the pipe a compresses the spring F sufficiently to swing the outer portion of the arm J in the direction indicated by arrow in Fig. 1 far enough to draw the contact-piece t out of engagement with the contact-piece H , 20 the electric circuit will be broken and the working of the compressor stopped. The movement of the arm J and the contact-piece t in the direction indicated by arrow puts the spring u under tension, and hence when the 25 free end of the contact-piece t reaches the end of the outer wall of the recess l the said spring will cause the contact-piece t to snap out of engagement with the arm G and to assume the position shown in Fig. 5 relative to the 30 arm J and by so doing will effect a quick breaking of the electric circuit. The parts will remain in the positions last stated until the pressure of the spring F is greater than that of the air in the cylinder A , when the 35 said spring will operate to move the piston B toward the right and through the medium of the said piston swing the arm J toward the arm G . When the contact-piece t incident to such movement of the arm J reaches the 40 beveled end m of the arm G , it will ride over said end and snap into engagement with the complementary contact-piece H , and thereby 45 complete the electric circuit and cause the resumption of working of the compressor.
- 50 The positive connection of the electric circuit may be on the contact-piece H and the negative connection of said circuit on the arm portion r , with which the contact-piece t is electrically connected, as indicated by the 55 conventional plus and minus signs in Fig. 1, or, if desired, the negative connection may be on the contact-piece H and the positive connection on the arm portion r .

When the electric circuit is broken, the 60 spring u operates to hold the abutment x against the edge of the arm portion r and the contact-piece t in the position shown in Fig. 5 relative to the arm G , so that said contact-piece t is in readiness to ride over the end m 65 of the arm G when the pressure of the spring

F is greater than the fluid-pressure, and the piston B is moved toward the right by the expansion of said spring.

Referring by letter to Fig. 6 of the drawings, M is an electric motor. N is a source 70 of electric energy; P , a fluid-pressure pump or compressor connected with and adapted to be operated by the motor; Q , a pipe interposed between and connecting the pump and the cylinder A of our novel controller; R , a 75 branch pipe designed to lead from the pipe Q to the point of use; S , an electric connection intermediate of the contact-piece H of the controller and the positive pole of the source of electrical energy, and T an electrical connection intermediate of the contact-piece t of the controller and the negative pole of the source of electrical energy. When the circuit in which the motor M , source of electrical energy N , and the controller are arranged is 80 broken, the motor will obviously stop and the compression of fluid-pressure cease, while when the said circuit is completed the motor and the pump or compressor will again be put in operation.

It will be gathered from the foregoing that our novel controller is automatic and reliable in operation and that its construction is simple and inexpensive and does not comprise any delicate parts, such as are likely to get 85 out of order after a short period of use.

We have entered into a detailed description of the construction and relative arrangement of the several parts embraced in the present and preferred embodiment of our invention 90 in order to impart a full, clear, and exact understanding of said embodiment and the workings thereof. We do not desire, however, to be understood as confining ourselves to such specific construction and relative arrangement 95 of parts, as such changes or modifications may be made in practice as fairly fall within the scope of our invention as claimed.

Having described our invention, what we claim, and desire to secure by Letters Patent, 100 is—

1. In an electric controller, the combination of a cylinder, a piston contained in the cylinder and arranged to be moved in one direction by fluid-pressure, other means for moving the piston in the opposite direction, a contact-piece, a swinging arm connected and movable with the piston, a swinging contact-piece on said swinging arm and arranged to be moved into and out of engagement with 115 the first-mentioned contact-piece, and a coiled spring connecting said swinging contact-piece and the swinging arm.

2. In an electric controller one end of which is arranged to be connected with a source of 120 fluid-pressure supply, a screw bearing in the opposite end of the cylinder and having a head movable within the cylinder, a piston also movable in the cylinder, a coiled spring contained in the cylinder and interposed be- 130

tween the head of the screw and the piston, a contact-piece, a swinging arm connected and movable with the piston, a swinging contact-piece on said swinging arm and arranged to be moved into and out of engagement with the first-mentioned contact-piece, and a coiled spring connecting said swinging contact-piece and the swinging arm.

3. In an electric controller, one end of which is arranged to be connected with a source of fluid-pressure supply, a cap disposed on the opposite end of the cylinder and having an aperture and also having a yoke provided with an aperture coincident with that first mentioned, a screw extended loosely through said apertures and having a head movable in the cylinder, a nut mounted on said screw and interposed between the cap and the yoke thereof, a piston movable in the cylinder, a coiled spring interposed between the head of the screw and the piston, a contact-piece, and a second contact-piece controlled by the piston and movable into and out of engagement with the first-mentioned contact-piece.

25 4. In an electric controller, the combination of a cylinder, a piston contained in the cylinder and arranged to be moved in one direction by fluid-pressure, other means for moving the piston in the opposite direction, an arm reaching laterally from the cylinder, a contact-piece carried by said arm and insulated from the cylinder, a swinging arm fulcrumed on the cylinder and connected at its inner end to the piston, a swinging contact-piece mounted on said swinging arm so as to move into and out of engagement with the first-mentioned contact-piece and insulated from the cylinder, and a coiled spring connecting said swinging contact-piece and the swinging arm.

35 5. In an electric controller, the combination of a cylinder, a piston contained in the cylinder and arranged to be moved in one direction by fluid-pressure, other means for mov-

ing the piston in the opposite direction, an arm fixed to and extending laterally from the cylinder, and having a recess in one side and also having a beveled outer end, a contact-piece fixed in said recess, an arm mounted in a pivotal manner on the cylinder and connected at its inner end with the piston, a swinging contact-piece mounted on the outer portion of said arm and insulated from the cylinder, and a spring interposed between said swinging contact-piece and the swinging arm. 55

6. In an electric controller, the combination of a fixed piece having a recess in its side, and also having a beveled end, a contact-piece arranged in said recess, an arm mounted to swing toward and from the fixed piece, means for swinging said arm, a swinging contact-piece mounted on the arm and movable into and out of engagement with the first-mentioned contact-piece, and a spring connecting the swinging arm and the swinging contact-piece. 65

7. In an electric controller, the combination of a fixed piece having a recess in its side, and also having a beveled end, a contact-piece arranged in said recess, an arm mounted to swing toward and from the fixed piece and having a lateral bolt, a contact-piece mounted to swing and move laterally on said bolt, a coiled spring arranged on the bolt between the head thereof and the swinging contact-piece, an abutment on the contact-piece arranged to engage the swinging arm, and a coiled spring connecting said arm and contact-piece. 75
